COMBINED BALE WIRE TYING AND CINCHING TOOL

Jay R. Guhl, San Leandro, Calif., assignor of a fractional
part interest to W. Dean Park, San Leandro, Calif.

Filed May 20, 1971, Ser. No. 145,589

Term of patent 14 years

Int. Cl. D8—05

U.S. Cl. D8—44

FIG. 1 is a perspective view of a combined bale wire tying and cinching tool showing my new design;

FIG. 2 is an elevational view on a reduced scale;

FIG. 3 is an edge view looking from the top of FIG. 2;

FIG. 4 is an elevational view showing the side opposite that shown in FIG. 2;

FIG. 5 is an end elevational view looking from the left of FIG. 2;

FIG. 6 is an end elevational view looking from the right of FIG. 2; and

FIG. 7 is an edge view looking from the bottom of FIG. 2.

I claim:

The ornamental design for a combined bale wire tying and cinching tool, as shown.
